UNITED STATES PATENT OFFICE.

JAMES L. HILDEBRAND, OF LYNN, AND HANS H. WANDERS, OF BROOKLINE, MASSACHUSETTS, ASSIGNEES TO THE FLINTKOTE COMPANY, OF BOSTON, MASSACHUSETTS, A CORPORATION OF MASSACHUSETTS.

MACHINE FOR PACKAGING ROOFING.

Application filed March 3, 1919. Serial No. 280,458.

To all whom it may concern:

Be it known that we, JAMES L. HILDEBRAND and HANS H. WANDERS, respectively a citizen of the United States and a subject 5 of Germany, residing at Lynn, in the county of Essex and State of Massachusetts, and at Brookline, in the county of Norfolk and State of Massachusetts, have invented new and useful Improvements in Machines for 10 Packaging Roofing, of which the following is a specification.

In the manufacture of such prepared roofing elements as shingles or shingle strips or slabs, it is customary, after subjecting the 15 sheet of felt to the usual saturating and coating instrumentalities (by which the sheet is first impregnated with pitch, asphalt or other waterproofing compound, coated with a higher-melting-point pitch or 20 asphalt, and surfaced with a partially embedded layer of crushed slate or other mineral), to pass the sheet progressively through a machine which cuts it into units, i. e. into individual shingles or into slabs or 25 strips equal in length to the width of two or more shingles. Such machines operate at high speed, and it has been the shop practice to employ a number of workmen stationed at the delivery end of the machine to 30 sort, count and stack the units.

The present invention has for its object to provide mechanism for use in connection with the unit-cutting machine for automatically stacking the units in groups, with the 35 same number of units in each group, so that they may be properly secured in packages for storage and shipment.

In accordance with the present invention, the stacking or grouping mechanism is co- 40 ordinated with the cutting machine, so as to receive the units delivered thereby, and arrange them in groups or stacks. In connection therewith, a conveyor may be employed for delivering the groups at some other 45 point where the stacks or groups may be bound with wire or otherwise packaged.

On the accompanying drawing,

Figure 1 represents in side elevation a machine for cutting sheets of roofing into 50 small units, such as shingles or slabs, and a stacking mechanism cooperating therewith.

Figure 2 represents an end elevation of the instrumentalities.

Figure 3 represents an elevation of the 55 stacking mechanism on a larger scale.

Figure 4 shows the stacking mechanism in side elevation.

Figure 5 represents a vertical longitudinal section through the stacking mechanism. 60

Figure 6 shows a portion of the mechanism by which the gate is operated to divert the units into different paths.

Fig. 7 represents a section on the line 65 7—7 of Figure 6.

Figure 8 represents a section on the line 8—8 of Figure 6.

Figure 9 represents a section on the line 9—9 of Figure 8.

Figure 10 is a diagrammatic representation of the stacking mechanism. 70

In explaining the principles of operation of the instrumentalities illustrated on the drawing as constituting an embodiment of the invention, it should be understood that 75 the invention is capable of various other embodiments, that the drawings are more or less conventional, and that the phraseology hereinafter contained is for the purpose of description and explanation and not 80 of limitation.

One of the serious problems which must be solved in the production of instrumentalities in stacking roofing units in evenly numbered piles or stacks arises from the 85 fact that the cutting machine operates continuously and at relatively high speed, and also from the nature of the roofing units which are usually surfaced with partially embedded crusher slate or grit and are therefore difficult to handle or manipulate. The severed units are continuously delivered in a constant stream from the cutting machine almost in contiguous end to end relation, and the mechanism for interrupting the 90 stream and diverting a predetermined number of units into one receptacle or holder and the next succeeding predetermined number of units into another receptacle or holder must operate evenly without excessive jar and at very high speed. In the machine which we shall herein describe, we have presented a solution of the problem which has proved to be satisfactory in commercial operation. 100

It is quite immaterial what particular form the cutting machine may take so long as it is capable of having the sheet of roof-

ing fed thereto and of cutting it either into shingles or slabs. Any one of a number of cutting machines may be employed for this purpose, although we have shown one which in its general features of construction and operation does not differ materially from those shown in the patents to Overbury Nos. 1,182,416, dated May 9, 1916, or 1,182,417, dated May 9, 1916.

10 The cutting machine, as conventionally shown, comprises a frame 10, which is supported at some distance from the ground or floor upon a base 11. At 12 and 13 are indicated cutters which may either slit the sheet into a number of longitudinal strips or else form therein a series of longitudinal slots, this depending upon whether the machine is for the purpose of producing oblong shingles, or shingle strips or slabs. At 14 there is indicated a chopping cutter designed to cooperate with a stationary blade by which the sheet is cut transversely so as either to sever the longitudinal strips into shingles of the desired length or else to cut the sheet transversely in lines intersecting the slots so as to produce serrated slabs or shingle strips. This machine is shown as simply one exemplification of a shingle-forming or slab-forming machine which may be used with instrumentalities embodying our invention. Any suitable power-transmitting mechanisms may be employed for effecting the feed of the sheet and the operation of the various cutters. As the units are cut from the sheet, they slide down a guide 15 and are delivered to an endless conveyor 16. This conveyor, which consists of a series of belts, is driven at a speed sufficiently high to effect the initial separation between the units delivered thereto from the guide 15 and to project them into the compartments as the same are formed from time to time by the swinging of the gates. As indicated, the conveyor is driven by pulleys 121 on the shaft 21, the latter being driven by a sprocket wheel 22 thereon, a sprocket chain 216 and a sprocket wheel 219 on the main drive shaft 19. The main drive shaft, by a pinion 217 and large gear 17, drives the knife shaft 18. The shaft 21 is journaled in a bracket 23 extending from one end of the frame 10. The upper stretch of the conveyor 16 is preferably inclined downwardly and outwardly so that the units carried thereby can be shot from the end of the conveyor into the stacking mechanism. The knife shaft 18 is geared by the two gears 24 and 25 to a shaft 26 having a sprocket wheel 27 from which power is conveyed to the operating instrumentalities of the stacking mechanism. The principle upon which the stacking mechanism is operated is diagrammatically shown in Figure 10. Between two spaced opposing walls *a* and *b*, there is a pivoted gate *c* over or under the upper end of which the units are delivered

from the conveyor. When the gate is in the full-line position, the units pass over the top of the gate into the temporarily formed receptacle *d*, the lower end of which is closed by the engagement of the lower end of the gate with the wall *b*. When a predetermined number of units have been delivered into this receptacle or compartment, the gate is quickly shifted to the dotted line position so as to bring the lower off-set end of the gate into engagement with the wall *a* forming temporarily a second receptacle or compartment *e*, into which a predetermined number of the units are delivered. As the gate swings from the full-line to the dotted line position, the stack of units in the compartment *d* are deposited in the box conveyor *f*. This conveyor moves transversely of the longitudinal lines of the cutting machine and the stacking mechanism so as to carry the stacks of roofing units delivered thereto to the front or rear of the machine where they may be deposited on the table or manually removed therefrom and placed in a binding machine for binding each stack or pile of units with straps or wires. It is necessary that the gate should move very rapidly from one position to another, and mechanism for this purpose is afforded as will be shown.

Proceeding now to a detailed description 95 of the stacking mechanism, it comprises the two angular frames 28, 29, at the front and rear sides of the mechanism. The lower ends of the frames are secured to and supported by standards 30, 31, the bases of 100 which are connected together by bars 32. At the front side, the frames 30, 31, are provided with bearing brackets 33, on which are supported the adjustable boxes 34 for a shaft 35 on which are mounted the sprocket 105 wheels 36 for a chain conveyor having a series of U-shaped boxes 37, the side walls of which are spaced far enough apart to receive an upright stack of roofing units. In Figure 2, the conveyor is illustrated as being 110 carried to the rear, the other sprocket wheels and driving mechanism not being illustrated. As a matter of incidental construction, the conveyor chain may be provided with cross bars 38 having rolls 39 movable 115 along the guides 40, 41 supported by the frames 30, 31. The conveyor is moved at sufficient speed to ensure that the stacks of roofing units, discharged into the boxes thereof, are carried to the rear before the 120 next discharge of units takes place.

The frame bars 28, 29, are connected together at their upper ends by the bars 43 upon which the gate is pivotally supported, as will be explained. Braces 44 and struts 125 45 may be utilized to ensure the rigidity of the framework. The bars 28, 28, are bridged by cross braces 48, 49, 50 and 51, and supported by said cross braces there is a wall consisting of one or more sheets 52 of metal 130

formed with parallel ribs 53. The plate 52 at its lower end overlaps a plate 54 which serves as a guide in directing the stack of units downwardly into the boxes of the conveyor as shown in Figure 5. At its upper end, the plate 52 is formed with the angular portion 55, and the extremity of the plate extends slightly beyond the frame bars 28, 28. Opposing the wall thus formed by the plates 52 and 54, there is another wall which consists of the two overlapping ribbed plates 56, 57. The plate 57 has lugs 58 attached thereto which are pivoted on cross shafts 59 supported by the frame bars 29. At its lower end, the plate 56 has similar lugs 60 which are pivotally supported upon the cross shaft 61 supported by the frame bars 29. The overlapping ends of these two plates may be temporarily secured together by screws and wing nuts 62, 63, so as to form a substantially continuous wall. The plate 57 is angular, as shown in Figure 5, for a purpose to be described. The upper portion of the plate 57 is approximately parallel to the plate 53, the latter being at an inclination greater than the angle of slip so that the individual units, as well as a stack thereof, will slide down it, when permitted. Between the two plates forming the opposing walls of an inclined chute, there is a gate, as previously explained, which may be constructed in any suitable or convenient way so that it will perform its allotted function. As shown, it consists of side bars 64, 64, having cross bars 65, 66 and 73. Bridging the side bars and secured to the under side of the cross bars 65 is a ribbed plate 67, the lower end of which has an angular portion 68 reinforced at its outer edges with side walls 69. The plate 68 serves as a stop against which the units are projected as they are delivered from the feeding and spacing conveyor. A second ribbed plate 70 is secured upon certain of the cross bars 65, and upon the cross bars 66. This plate is angular, its upper portion 71 lying at an acute angle to the corresponding portion of the plate 67 and meeting it at its upper edge with the result that the upper end of the gate is wedge shaped. Between the angular portion 71 of the plate 70 and the main body portion is the portion 72, attached to the cross bar 73 and perpendicular to the body portion. This formation is for the purpose of permitting the individual roofing units to pass over the angular portion 71, and to fall upon the body portion, thus ensuring the stacking of the units on the body portion of the plate 70. The formation of the plate 52, with the offset portion 52^a, is for the same purpose, i. e. so that each shingle shall drop upon the face of the preceding shingle.

The gate is pivoted or hung upon two stud shafts 74, 74, placed in bearing brackets 65 or lugs 75 supported upon the members

of the frame. The stacking mechanism is so positioned in relation to the unit-forming machine that the chute formed by the plates 52 and 51 can receive the units delivered therefrom, and so that the units will pass under the gate when the latter is in one position and will pass over it when it is in the other position, as shown in Figure 1. When the gate is in the position shown in Figure 5, the roofing units are delivered into the compartments formed by the plate 57, and the lower end of the gate being projected by the feeding conveyor against the angular end of the plate 57 and resting upon the gate which serves as a movable support therefor; and, when the gate is swung to its other extreme of movement, they are delivered into the compartment formed by the plate 53, the gate and the extension 68, which in this instance forms a movable stop for the roofing units projected into the compartment. When the gate swings from one position to the other, it opens one compartment and delivers the stack of units caught and stacked therein and automatically closes the other compartment to catch and stack the next succeeding units therein. The delivery throat of the chute, between the lower ends of the plates 56 and 54, registers with the boxes on the conveyor there-beneath; and the inclination of the members on which the roofing units rest, as they are being stacked, ensures that the pile or stack will immediately slide downwardly into the conveyor boxes when it is released. The mechanism, by which the gate is moved, is operated from the unit-forming or cutting machine and is timed so that the gate will be moved only when a predetermined number of units are stacked, thus ensuring that all the stacks as delivered to the delivering conveyor are equal in number of units. This mechanism is shown in Figures 1, and 6 to 9 inclusive. Power is imparted thereto by a sprocket chain 80 connecting the sprocket 27 on the shaft 26 with a sprocket 81 on a shaft 82. The latter is mounted in the front frame bar 28. A cross bar 83 bridges the frame bars 28, 29, and in it is journaled a shaft 84 which is rotated by any suitable reducing gearing interposed between it and the sprocket 81. As shown, there is compounded with sprocket 81 a smaller sprocket 85 which by chain 86 drives sprocket 87 on shaft 88, the latter having on its front end a pinion 89 intermeshing with the large gear 90 on shaft 84. The parts are so timed that the shaft 84 rotates once during a plurality of revolutions (say 100 for instance) of the cutter 125 shaft 18. On the inner end of shaft 84 there is a hub 91 provided with an arm 92, with a circular outer concentric flange 93, and with inner arcuate concentric flanges 94, 94, which form between them a circular 130

groove or guideway. The gate has a pin or roller 95 projecting from the front side thereof into the groove or guideway as shown in Figures 8 and 9. A helical spring 96 is connected to the pin 95 and to a pin 97 on the outer end of the arm 92, by means of hooks 98, 99, secured to the ends of the spring. The springs tend to pull the free end of the gate toward the outer end of the arm, but this is resisted by the arcuate flanges 94 until the pin 95 registers with one or the other of the gaps 100, 101, between the ends of the flanges. Assuming the parts to be in the position conventionally shown in Figures 8 and 9, with the pin 95 registering with gap 100, as a result of the rotative movement of the hub 91, the spring 96 will snap the pin through both gaps 100, 101, until it engages the flange 93, as a result of which the lower end of the gate will be moved with great rapidity to the left. During the continued rotation of the hub and the arm 92, the pin 95 will be held in the last-mentioned position until the gap 100 again registers with the pin, whereupon the spring, which has been again stretched, will snap the pin 95 to the right and move the lower end of the gate to the right. Thus, during each complete rotation of the shaft 84 and hub 91, the gate will be swung first in one direction and then in the other, the intervals between these movements being identical, and being coordinated with the revolutions of the knife of the cutter, to ensure the same number of roofing units always being delivered for a shingle stack. If desired, the pin 95 may be mounted in the slide 102 arranged in a guideway in the front side bar 64 of the gate and extend through a slot in a plate 103 secured thereto. Equalizing springs 104, 104, in a recessed block 105, bear against the inner end of the pin 95. To assist in holding the lower end of the gate in one position or the other, and to equalize the weight of the stock thereon, we may employ a helical spring 107 connected at one end by a hook with a pin 108 on the rear side of the gate near its lower end, and connected at its other end with a screw eye 109 on a link 110. The latter is pivoted on a stud 111 extending upwardly and to the left from the rear bearing bracket 75, the axes of stud 111, stud shafts 74 and shaft 84 being all in approximately the same plane. The link 110 is formed with an elliptical loop through which the rear stud shaft 74 extends, so as not to interfere with the swinging movement of said link. As the pin 108 swings in one direction or the other, past its dead center position in reference to the axis of the shaft 84, the spring 107 tends to hold it alternately in its normal positions of rest, and to counterbalance the gradu-

ally increasing weight of the stack being formed.

In order that the roofing units may be guided from the conveyor 16 until they enter the stacking machine, there are a plurality of strip guides 115 which at one end are supported on a cross rod 116, extending between the upper ends of the frame bars 28, and at the other ends are hooked over the shaft. These guides are located between the individual chains which constitute the conveyor 16 and they have angular portions 118 which guide the units from the chains into the stacking mechanism. The upper end of the gate moves from a position below the angular portions 118, where the roofing units shoot over it, to a position above said portions, where said units pass under the end of the gate.

In operation, the sheet of roofing is fed continuously by the usual feeding rolls (not shown) through the unit-forming machine, and is formed into units of the desired character. As finally formed or severed the units are received by the conveyor 16, which constitutes an intermediate feeding mechanism, which, travelling at a higher rate of speed than the sheet of roofing, spaces the units apart in the direction of their travel, so that there is an appreciable interval between the rear edge of one unit and the forward edge of the next one succeeding it. Assuming that the gate is in the position shown in Figure 5, the units pass over the inclined end of the gate and drop onto the lower end of the gate, their further progress being stopped when they abut against the vertical portion of plate 57 which thus serves as a stop for the units. Each unit passes over the preceding unit, and a pile or stack is gradually formed, until a predetermined number have been stacked and are supported on the plate 70. During this time, through the speed-reducing gearing, the shaft 84 is being slowly rotated, and, when it has moved through an arc of approximately 180° , the arm 92 reaches a position about perpendicular to the gate and the springs 96 draw the pin 95 through the gaps between the arcuate flanges 94 and thus shift the gate from the full-line position in Figure 4 to the dotted-line position. As this occurs, the stack or stacks of roofing units, which were supported by the lower end of the gate, drop downwardly into the boxes of the delivery conveyor and are carried laterally or rearwardly from the machine to a point where they may be removed or delivered to a suitable receptacle. The timing is such that the upper end of the gate is lifted just before the forward edge of an oncoming roofing unit reaches it, so that the unit passes under the upper end of the gate. The gate remains in this position un-

til a predetermined number of units are delivered under the edge of the gate to form the stack, whereupon, the shaft 84 having rotated through an arc of 180°, the springs 96 snap the pin through the gap between the flanges 94 to the right, thus swinging the upper end of the gate forwardly and downwardly to cause the units to pass over it. The units successively engage the plate 68 which forms a stop and they are supported on the rib plate 52, from which they are dropped when the gate is again swung to its alternate position.

In lieu of employing ribbed plates to form the opposing walls in the stacking mechanism, strips of wood or metal may be employed, as will be readily understood. The reason for providing the two overlapping hinged or pivoted plates 56, 57, instead of a single plate, is to permit them to be swung about their axes and thus afford access to the interior of the chute, from the end of the machine.

In considering the instrumentality which we have termed the gate, it will be seen that it performs two different functions, which, if desired, could be performed by two different instrumentalities. That is, the upper end of the gate performs the function of a switch for directing the flow of units from the forming or cutting machine, automatically and alternately into separate paths. The lower end of the gate serves the function of arresting the flow of diverted units until a pile or stack thereof is formed, and then automatically delivering the formed pile or stack. Thus the machine is provided with a switch or means for intermittently diverting or directing the flow of units into divergent paths, and an arrestor or means for arresting the diverted units until a pile or stack thereof is formed, although, as we have said, these elements for the sake of simplicity of construction in the present embodiment of the invention are formed together in a single element or instrumentality, since the same operating mechanism may be employed for actuating the switch and the arrestor.

Having thus explained the nature of our said invention and described a way of making and using the same, although without attempting to set forth all of the forms in which it may be made or all of the modes of its use, what we claim is:

1. The combination with a conveyor for feeding articles in succession, of means for arresting and supporting the said articles in superposed relation as they are fed thereto by said conveyor, a conveyor below said means, and automatic mechanism by which said articles are dropped into said conveyor without reversing the position of said articles when a predetermined number thereof

have been delivered to said arresting and holding means.

2. The combination of a conveyor adapted to feed roofing units in succession at relatively high speed, a stop and a support located below said conveyor to arrest and support said units in superimposed relation, a conveyor below the last-mentioned mechanism, and automatic mechanism for causing said units to be dropped onto said last-mentioned conveyor without reversing the position of said articles when a predetermined number thereof have been piled on said supporting means.

3. The combination of a receiving conveyor, a stop or arrester, means for feeding the articles in succession against said stop or arrester, and means located to receive the articles as they are fed against said stop and for supporting them until a predetermined number have been delivered and then to drop them onto said conveyor without reversing the position of said articles.

4. The combination of a receiving conveyor, a feeding conveyor for feeding the articles successively, a support below the end of the feeding conveyor onto which said articles are delivered by the feeding conveyor in superimposed relation, a stop against which said articles are fed by said feeding conveyor, and automatic mechanism for causing said articles to be delivered from said supporting mechanism without reversing the position of said articles when a predetermined number have been piled thereon by said feeding conveyor.

5. The combination of a movable support, a stop, means for feeding the articles successively into engagement with said stop and onto said movable support, a receiving conveyor below said support, and means for automatically operating said support, when a predetermined number of articles have been delivered thereon, to drop them onto said conveyor without reversing the position of said articles.

6. The combination of a stationary support arranged at an inclination, a movable stop, means for feeding the articles successively against said stop and onto said support, a receiving conveyor below said support, and mechanism for automatically moving said stop, when a predetermined number of said articles have been delivered onto said support, to permit them to be dropped onto said receiving conveyor without reversing the position of said articles.

7. In combination, an endless conveyor adapted to feed the articles in spaced-apart relation, a stop located beyond the conveyor against which said articles are projected by said conveyor, a support arranged to receive said articles in piled relation, and mechanism operated automatically, when a pre-

5   terminated number of said articles have been piled on said support, to cause said articles to be dropped from said stop and support without reversing the position of said articles.

10   8. A stacking mechanism adapted to be arranged at the delivery end of a unit-delivering machine, and comprising a stationary chute, a switch for delivering predetermined numbers of units alternately into separate paths, an arrester in said chute for arresting the units in each path until a stack thereof is formed, and means for automatically actuating said switch and said arrester.

15   9. A stacking mechanism adapted to be arranged at the delivery end of a unit-delivering machine, and comprising a chute arranged to receive the units delivered by said machine, a gate arranged in said chute having means for diverting predetermined numbers of units alternately into separate paths, said gate having means for arresting the flow of units until a group or stack thereof is formed, and then releasing said group or 25 stack, and operating mechanism for actuating said gate automatically.

20   10. The combination with a feeding conveyor, a stacking mechanism adapted to receive the articles delivered by said conveyor, and comprising means for automatically and intermittently directing the flow of the articles through different paths into separate piles or stacks, and means by which said stacks are automatically released and 35 dropped when a predetermined number of articles have been piled in said stacks respectively.

30   11. A stacking mechanism comprising a chute, a gate therein, means for automatically operating said gate alternately to divert predetermined numbers of articles delivered to said chute in one or the other of separate paths and to arrest the diverted articles in the chute until a stack thereof is 45 formed, and then to drop the completed stack.

35   12. A stacking mechanism comprising a chute and a gate therein cooperating alternately with the opposite walls of the chute 50 to form receiving and stacking compartments in the chute, said gate being provided with a switch for diverting the articles into said compartments, and mechanism for automatically operating said gate upon the delivery of a predetermined number of articles into one or the other of said compartments.

40   13. Stacking mechanism comprising a chute and a gate therein cooperating alternately with the opposite walls of the chute 55 to form receiving and stacking compartments, said gate being provided with a switch for diverting the units into one or the other of such compartments until a predetermined number of units has been delivered

thereto, and mechanism for operating said gate automatically.

14. Mechanism for stacking or grouping prepared roofing units, comprising a chute having opposing walls, an oscillatory gate arranged between said walls to cooperate in alternation therewith to form unit-receiving and stacking compartments and provided with a switch to divert the units into said compartments, and mechanism for automatically oscillating said gate simultaneously to deliver a stack from one compartment and guide the units into stack-formation in the other compartment.

15. Mechanism for stacking or grouping prepared roofing units, comprising a chute having opposing walls, an oscillatory gate arranged between said walls to cooperate in alternation therewith to form unit-receiving and stacking compartments and provided with a switch to divert the units into said compartments, and mechanism for automatically oscillating said gate, in combination with means below said gate to receive and remove the stacks liberated from the alternately-formed compartments.

16. Mechanism for stacking or grouping prepared roofing units, comprising a chute having opposing walls, an oscillatory gate arranged between said walls to cooperate in alternation therewith to form unit-receiving and stacking compartments and provided with a switch to divert the units into said compartments, and mechanism for operating said gate including a revoluble arm thereon, a spring connection between the arm and the gate, and devices restraining said gate from movement except at predetermined points in the revolution of said arm.

17. A mechanism for stacking or grouping prepared roofing units comprising non-horizontal opposing walls forming a chute, a pivoted gate arranged to engage said walls in alternation to form stacking compartments and provided with a switch to control the passage of the units into said compartments, and mechanism for actuating said gate including a rotary shaft, an arm thereon, a pin on said gate, a spring connection between said pin and the free end of said arm, and segmental guides disposed about the axis of said shaft for restraining the operation of said gate except at predetermined points in the rotation of said shaft.

18. A mechanism for stacking prepared roofing units, comprising an inclined chute with opposing walls, one of which is recessed to form a unit-receiving space, a gate pivoted between said walls and having a unit-arresting end adapted to engage said walls in alternation to form therewith a stack-forming compartment, said gate hav-

ing a switch for controlling the passage of the units into one or the other of said compartments, said gate being formed in rear of said switch to provide on its upper portion a unit-receiving space, and means for automatically operating said gate.

19. In a stacking machine, a frame therefor, a wall in said frame, means to deliver units to be stacked upon said wall, means 10 cooperating with said wall to retain the units thereon until a predetermined number have been deposited and formed into a stack or bundle and to release the stack or bundle when formed, said wall being 15 inclined to the horizontal equal to or greater than the angle of slip so that the stack or bundle of units when released slide by gravity down the inclined wall.

20. In a stacking machine, a frame therefor, an inclined wall in said frame, means to deliver flat elements to be stacked in a pile upon said wall, said wall being inclined at an angle such that the elements and the stack of elements formed thereof will tend 25 to slide down said wall, and means to retain the elements on said wall until a stack has been formed, and then to release the stack.

21. In a stacking mechanism, a frame 30 therefor, an upper and a lower inclined wall in said frame, a gate or switch pivoted between said walls and adapted to contact at its lower end alternately with the upper and with the lower walls to form 35 receptacles to receive units successively deposited therein in superposed relation, the angle of the lower wall and the angle of the gate, when its lower end contacts with the lower wall, being such that the stacks of 40 units will tend to slide thereon when free to move.

22. In a stacking machine, a frame therefor, upper and lower inclined walls in said frame, a gate or switch pivoted to said 45 frame, having its lower end so arranged that it is adapted to contact with the lower ends of the upper and lower walls, forming receptacles respectively therewith for the reception of units successively delivered 50 thereto, means on the upper end of the lower wall to guide said units in their course so that each successive unit delivered to the receptacle formed therewith by the gate or switch will be deposited on top of the preceding ones in a stack or bundle, and means 55 on the upper end of said gate for guiding the units delivered to the receptacle formed between the upper wall and said gate so that each successive unit will be deposited 60 on top of the preceding ones to form a stack or bundle.

23. In a stacking machine, a frame therefor, an inclined wall in said frame, means for delivering units to said stacking ma-

chine to be stacked, means on the inclined 65 wall for guiding the units so that they will be deposited on said wall one upon another in a stack or bundle, and means for retaining said units upon said wall until a predetermined number have been deposited 70 in the stack or bundle, and then automatically releasing the stack or bundle.

24. In a stacking machine, a frame therefor, an inclined wall in said frame, means for delivering units to said stacking machine to be stacked, means on the inclined wall for guiding the units so that they will be deposited on said wall one upon another in a stack or bundle, means for retaining 75 said units upon said wall until a predetermined number have been deposited in the stack or bundle, and automatic means for releasing said stack or bundle when the predetermined number of units have been deposited thereupon.

25. In a stacking machine, a frame therefor, inclined upper and lower walls therein, a gate or switch pivoted between said upper and lower walls and adapted to contact at its lower end with the upper and lower walls to 90 form receptacles alternately therewith for the reception of units to be stacked, means for delivering such units to said receptacles, and means on the upper end of said lower wall and on the upper end of said gate, for 95 guiding the units in their course so that they will be deposited one upon another in a stack or bundle in the respective receptacles formed alternately by said gate in conjunction with the lower wall and with the upper 100 wall.

26. In a stacking machine, a frame therefor, inclined upper and lower walls therein, a gate or switch pivoted between said upper and lower walls adapted to contact at its 105 lower end with the upper and lower walls to form receptacles alternately therewith for the reception of units to be stacked, means for delivering such units to said receptacles, means on the upper end of said lower wall and means on the upper end of 110 said gate for guiding the units in their course so that they will be deposited one upon another in a stack or bundle in the respective receptacle formed by said gate 115 with the lower wall and with the upper wall, and means for releasing said stack or bundle when a predetermined number of units have been deposited.

27. In combination, a shingle stacking 120 machine and a conveyor, said stacking machine having a frame, a wall in said frame, inclined to the horizontal at an angle equal to or greater than the angle of slip and adapted to receive units thereon to be stacked, means associated with said wall to prevent slipping of the elements from the lower end of said wall until a predetermined 125

number of units have been deposited in a stack or bundle, a receptacle on said conveyor, and means whereby the stack or bundle of units is deposited in the receptacle with the units in a vertical position.

28. In combination, a shingle stacking machine and a conveyor associated therewith, said stacking machine having a frame and a wall therein, said wall being inclined 10 at an angle to the horizontal, equal to or greater than the angle of slip, so that units or stacks of units thereon will tend to slide thereon, means for delivering units to be stacked on said plate one upon another, 15 means to hold said units on said wall until a predetermined number of units have been deposited one upon another to form a stack and to release said stack when formed, and a receptacle on said conveyor adapted to be brought into position to receive said stack from the stacker when released, the relation 20 of the parts being such that the stack is delivered to the last-mentioned receptacle with the units in an upright position.
29. In combination, a stacking machine comprising a frame, a wall therein having an inclination to the horizontal equal to or greater than the angle of slip, means to deliver units to be stacked onto said inclined wall one upon another in a stack, 25 means to hold the units on said wall until a predetermined number have been deposited in said stack and to release the stack when formed, a conveyor having one end thereof adjacent the lower end of said wall, receptacles on said conveyor adapted to receive the stacks of units, means associated 30 with said stacking machine and conveyor for guiding the stacks from said stacking machine to said receptacle so that the units in the stack will be deposited in the receptacle in a vertical position.

30. In combination, a stacking machine having a frame, a wall supported in said frame at an inclination to the horizontal equal to or greater than the angle of slip, means to deliver units onto said wall so as to form a stack thereon, means to limit movement of the units on said wall until a stack of a predetermined number of units 45 has been formed and to release said stack when formed, a receptacle adapted to be located below the lower end of said wall, and means to guide the stack to said receptacle 50 so that it will be deposited in said receptacle with the units resting on their edges.

31. In combination, a stacking machine having a frame, a conveyor arranged at an angle less than the angle of slip and for delivering units to be stacked to said stacking machines, a wall in said frame inclined at an angle equal to or greater than the angle of slip, means associated therewith to so guide the units that they will be deposited on said

wall one upon another in a stack, means associated with said wall against which the elements impinge when delivered to form said stack, said means preventing further progress of the units until a stack of a predetermined number has been formed and releasing 65 said stack when formed, a receptacle adapted to be brought below the lower end of said wall in position to receive the stack as it slides therefrom, and means to guide said stack when released so that it will be delivered to said receptacle with the units thereof in upright position.

32. In combination, a stacking machine having a frame and a wall in said frame inclined to the horizontal at such an angle that 80 elements deposited thereon will tend to slide thereon and be precipitated from its lower end, means to deliver elements so that they will lie flat on said wall one upon another, means to limit the movement of said element 85 on said wall until a predetermined number have been deposited one upon another in a stack and to release said stack when so formed, a receptacle adapted to be brought into a position relative to the lower end of 90 said wall so as to receive said stack from said wall, and means to guide said stack in delivering the same to said receptacle so that the stack will be delivered thereon.

33. In combination, a stacking machine 95 having a frame, upper and lower walls in said frame, a switch pivoted to swing its lower end into contact with the lower ends of said walls to form unit-receiving receptacles therewith, means for delivering units upon 100 said switch flat one upon another to form a stack when its lower end is in contact with said upper wall, and upon said lower wall when said switch is in contact therewith, said switch and said lower wall being inclined to 105 the horizontal at an angle or to greater than the angle of slip, so that the units or stacks of units thereon will tend to slide therefrom by gravity when released, a conveyor having 110 receptacles adapted to be brought in position relative to the lower ends of said switch and of said lower wall to receive the stacks therefrom, and means for depositing said stacks in said receptacles.

34. In combination, a stacking machine 115 having a frame, a wall supported in said frame at an angle to the horizontal equal to or greater than the angle of slip, means for depositing units thereon, means for limiting the sliding of said units from said wall until a predetermined number are deposited in a stack or bundle, said limiting means being adapted to release said stack or bundle when formed, and means at the lower end of said wall for guiding said stack or bundle so that 120 the stack or bundle will be deposited in a receptacle placed beneath the inclined wall with the units resting on their edges.

35. In combination, a unit stacking machine, means for delivering units to said machine, said means being sloped at an angle less than the angle of slip and being power driven, said stacking machine having a wall located at an angle equal to or greater than the angle of slip, said delivery means being adapted to deliver units upon said wall one upon another in a stack, and automatic 10 means for limiting movement of said units on said wall until a predetermined number have been delivered and for releasing the stack when formed.

36. In combination, a unit stacking machine, means for delivering units to said machine, said means being sloped at an angle less than the angle of slip and being power 15

driven, said stacking machine having a wall located at an angle to or greater than the angle of slip, said delivery means being adapted to deliver units upon said wall one upon another in a stack, automatic means for limiting movement of said units on said wall until a predetermined number have been delivered and for releasing the stack when formed, a movable receptacle adapted to be brought adjacent the lower end of said wall, and means associated with said wall adapted to guide said stack to said receptacle so that the units will rest therein on their edges. 30

In testimony whereof we have affixed our signatures.
